UNITED STATES PATENT OFFICE

HERMAN E. BLEIER, OF CHICAGO, ILLINOIS

DESIGN FOR AN ELECTRIC-LIGHT-BULB JACKET OR SIMILAR ARTICLE

Application filed December 27, 1929. Serial No. 33,946. Term of patent 14 years.

To all whom it may concern:

Be it known that I, HERMAN E. BLEIER, a citizen of the United States, residing at Chicago, in the county of Cook and State of Illinois, have invented a new, original, and ornamental Design for an Electric-Light-Bulb Jacket or Similar Article, of which the following is a specification, reference being had to the accompanying drawing, forming a part thereof.

Fig. 1 is a side view of the design embodying my invention; and

Fig. 2 is a plan view of the same.

I claim:

The ornamental design for an electric light bulb jacket or similar article as shown.

HERMAN E. BLEIER.
